UNITED STATES PATENT OFFICE.

JACOB J. NICHOLS, OF BROOKLYN, AND WILLIAM S. McLEWEE, OF NEW YORK, N. Y.; SAID McLEWEE ASSIGNOR TO SAID NICHOLS.

DESIGN FOR A LAMP, &c.

SPECIFICATION forming part of Design No. 12,746, dated February 7, 1882.

Application filed November 2, 1881. Term of patent 7 years.

To all whom it may concern:

Be it known that we, JACOB J. NICHOLS, of Brooklyn, in Kings county, and State of New York, and WILLIAM S. McLEWEE, of New York, in the county and State of New York, have invented a certain new and original Design for Lamp Globes or Shades, of which the following is a specification.

Our design consists in a globe for a lamp, having opposite flattened portions. Such globe may be used to form a part of a lamp-stand or as a shade to surround the burner.

In the accompanying drawings, Figure 1 is a side view of a lamp embodying our design, and Fig. 2 is a plan or top view of said globe and the base of the lamp.

Similar letters of reference designate corresponding parts in both figures.

A designates a base, which may be of metal. B designates a globe forming the body, which may be of glass or other silicious material, and ornamented or decorated to suit the taste. This globe is of circular profile at one part, but has two flat or approximately flat portions or sides, b, as clearly shown in the drawings. Near the top and bottom it has beads a, and beyond these beads it has rims c.

C designates a lamp, which may be of any approved style. It is shown as set partly into

and supported on the top of the body B; but it might be set down on the base A, so that its burner will be within the body B, in which case the said body would also constitute a shade for the lamp.

D designates a globe, which forms a shade for the lamp, and is made of any silicious material, and decorated, if desirable. It is of the same shape of the body B, having a circular profile at one part and approximately flat portions or sides d at opposite points. As shown, it has no beads or rims corresponding to the beads a and rims c of the globe B, forming the body. A globe of the configuration described and shown has a very attractive appearance, and adds greatly to the ornamentation of the lamp in which it is used.

This design may be embodied in other lamp-fixtures—for instance, in oil or gas chandeliers.

What we claim as our invention, and desire to secure by Letters Patent, is—

A globe for a lamp, having opposite flattened portions, substantially as herein described.

JACOB J. NICHOLS.
